SIMON B. HESS, OF NEW YORK, N. Y.

BURGLAR-ALARM TRAP.

Application filed December 19, 1925. Serial No. 76,405.

This invention relates to electrically operated alarm signals, particularly to what are known as burglar alarm traps.

It is customary to provide in burglar alarm systems an alarm circuit and a controlling circuit therefor, the latter including a spring-pressed switch member operated by a trip cord. The trip cord is secured at one end to the switch member, normally holding the switch in neutral position, while the other end of the trip cord is fastened to a door or window, or positioned so an intruder will brush against it. When the cord is pulled or broken the switch member moves to change the condition of the controlling circuit and thereby causes actuation of the alarm. With this arrangement, if the owner of the premises wishes to keep the alarm inoperative during the day time, he can leave the electrical circuits in operative condition and hold the switch member in neutral position by tying the cord to a convenient object. The objection to this procedure is that he may leave the premises in the evening forgetting to connect the cord in its operative position.

One of the objects of this invention is to provide an arrangement of parts in the supervising circuit in which the cord or wire which holds the circuit controller in normal position is itself a conductor and is a part of the supervising circuit. The circuit is so arranged as to render it necessary to place the trip wire in protective position before the alarm can be set.

A further object of the invention is to detachably connect the trip wire to the pivoted switch member in such a way that contact with the wire will move the pivoted member in one direction to a sufficient extent to change the normal condition of the supervising circuit and cause operation of the alarm. Simultaneously the wire is freed from its connection with the switch member, whereupon, by the operation of a spring connected to the pivoted member, the latter is moved to and held in such a position with relation to the circuit of which it forms a part, that the controlling circuit remains in condition to cause or permit the continuance of the alarm.

While I have disclosed a preferred embodiment of the invention for purposes of illustration, it should be understood that the structure may be modified in various ways without departure from the true spirit and scope of the invention, as hereinafter defined and claimed.

In the drawings:—

Fig. 1 is a diagrammatic view showing the electrical circuits.

Fig. 2 is a plan view of the controlling switch.

Fig. 3 is a side elevation of the switch box, the front side having been removed.

Fig. 4 is a detail view showing the mounting of the switch member.

Referring more particularly to the drawings, there is shown at 5 a base carrying a box-like structure having a top 6. A switch member 7 is pivotally carried on the under side of the top by a bolt 8. A conductor strip 9 is held in electrical contact with the switch member by bolt 8, as shown in Fig. 4, and extends to a point outside the box where it is provided with a binding post 10. A conductor strip 11 extends across the base at 75 the front of the box and carries binding posts 12 and 13 outside the box. Contact members 14 and 15 are mounted on conductor 11 in such a manner as to contact with the switch member 7 at certain times.

The switch member is biased by a spring 16 toward stop 17 mounted on top 6. The outer end of the switch member is notched, as indicated at 18, the outer ends of the notch being curved as shown. The trip wire 20 passes over a pulley 21 mounted on the box and carries a ring 19 passed over one prong of the notched end of the switch member. The opposite end of the trip wire is secured to a pointed contact member 22 which is frictionally gripped between two curved spring members 23 mounted on a base 24.

The members 23 are connected to battery 25 by a conductor 26, the battery being grounded at 27 and a wire 28 connecting the opposite side of battery 25 to the binding post 13. A conductor 29 connects binding post 12 to an alarm bell 30, the bell being connected to one side of a battery 33 by conductor 35. The opposite side of battery 33 is connected to contact 36 by a conductor 34.

A conductor 37 connects the binding post 10 to both units 38 and 39 of an electromagnet and a conductor 40 connects the electromagnet to the contact 41. A conductor 42 connects with conductor 37 between the units of the electromagnet and is grounded at 43.

A pivoted armature 32 is mounted in operative relation to the electromagnet and is free to move against either of the contacts 36 or 41. A wire 31 connects the armature to conductor 29.

The operation of the device is as follows:

When the trip wire 20 is placed in protective position with contact member 22 gripped between spring contacts 23, the switch member 7 will be held in a neutral position between contacts 14 and 15, as shown in Figs. 1 and 2. The current then flows through the supervisory circuit in the following manner; from battery 25 through conductors 28, 11, 10 29, 31 to armature 32, thence through contact 41 conductors 40, 37, switch member 7, trip wire 20, contact members 23, conductor 26 back to the battery 25. This current energizes the electromagnet which retains the armature, thereby maintaining the armature in raised position. The supervisory circuit is then in protective position and the alarm circuit is inoperative.

If an intruder should brush against the trip wire 20 without disconnecting its ends, the switch member 7 would be moved against either of the contacts 14 or 15, thereby short-circuiting the current from conductor 28 directly into switch member 7 and thence via the trip wire back to the battery. This would cut out the electro-magnet from the supervisory circuit and allow armature 32 to fall against contact 36, thereby completing the alarm circuit as follows: from battery 33, 20 through conductors 34, 32, 31 and 29 to the bell, and thence through conductor 35 back to the battery.

If trip wire 20 should be broken or disconnected at either end in such a violent manner as to cause the switch member 7 to first move against contact 14 before the circuit through wire 20 is broken, then the electro-magnet will be entirely short-circuited as outlined above, putting the alarm circuit into 35 operation. After the switch member is released from the control of the trip wire, the spring 16 will move the switch member into engagement with contact 15 (Fig. 1) and current will flow only through the unit 38, which is not strong enough to lift armature 32, and hence the alarm will continue to operate.

If the intruder should break or remove the trip wire, the switch member would be moved by spring 16 against contact 15. In this position the current would flow through unit 38 of the electro-magnet as follows; from battery 25, through conductors, 28, 11, 7, 37

to unit 38, thence through conductor 42 to ground 43, to ground 27 and back to battery 25. At the same time current would flow through unit 39 as follows: from battery 25, through conductors 28, 11, 29, 31, 32 and 40 to unit 39, thence via wire 42 to ground 43, to ground 27 to battery 25. The current is therefore passing through unit 38 in a direction opposite to the current passing through unit 39. These units will therefore be oppositely polarized, one attracting and the other repelling armature 32, and the armature will therefore drop, completing the alarm circuit.

The provision of this type circuit insures the proper setting of the trip wire, since a circuit through the trip wire is necessary to place the supervisory circuit in protective condition. This is true because it is only when current is flowing through the trip wire that both units of the electro-magnet are energized to attract the armature 32, and the combined attraction of both units is needed to raise the armature 32, thereby putting the supervisory circuit in protective condition.

I claim:—

A burglar alarm system comprising an alarm circuit, an armature forming part of said alarm circuit, a pair of coils for holding said armature in position to open the alarm circuit, a pivoted switch arm, a conductor connecting the switch arm to both of the coils in series, a contact on each side of the switch arm, a second conductor connecting the contacts to each other, a third conductor connecting the second conductor to the armature, a source of electrical current, a fourth conductor connecting the second conductor to one side of the source of current, a trip wire conductor connecting the free end of the switch arm to the other side of the source of current, means biasing said switch arm to hold said trip wire conductor under tension, and sixth conducting means connected at one end between the said coils and leading to the source of current at a point opposite to that connected to the fourth conductor, the coils being so wound that when the current passes through the sixth conducting means the coils will be oppositely polarized.

In testimony whereof I affix my signature.

SIMON B. HESS.
